UNITED STATES PATENT OFFICE.

JOHN C. WILSON, OF BOSTON, MASSACHUSETTS, ASSIGNOR TO THE MUNICIPAL SIGNAL COMPANY, OF PORTLAND, MAINE.

SIGNAL-BOX.

SPECIFICATION forming part of Letters Patent No. 448,400, dated March 17, 1891.

Application filed May 17, 1887. Renewed February 18, 1891. Serial No. 381,809. (No model.)

To all whom it may concern:

Be it known that I, JOHN C. WILSON, of Boston, in the county of Suffolk and State of Massachusetts, have invented an Improvement in 5 Signal-Boxes, of which the following description, in connection with the accompanying drawings, is a specification, like letters on the drawings representing like parts.

This invention has for its object to provide 10 a signal-box with a multiple signal-transmitting apparatus, whereby several different signals may be transmitted at the will of the operator; and the invention consists in the combination, with the contact-pen, of a series of 15 signaling-surfaces movable in a direction parallel with the axis of rotation of the contact-pen to present one or another signaling-surface to the contact-pen. The signaling-surfaces are moved, preferably, by a pointer, 20 while a suitable motor mechanism is employed to rotate the contact-pen.

Figure 1 shows in front elevation a signal-box, the face-plate of which is broken away to display the signal-transmitting apparatus 25 in elevation; and Fig. 2 a side elevation of the signal-transmitting apparatus.

The contact-pen a is fixed to a hub or wheel a' , fast to a shaft a^2 , having its bearings in a suitable frame-work inclosed within the box 30 A. A leading-wheel a^3 is also secured to the shaft a^2 , against which wheel bears a contact-pen a^4 , connected with the line.

A motor mechanism is employed to rotate the shaft a^2 , which is herein shown as comprising a pinion 2, fixed to the shaft a^2 , and meshing with a toothed wheel 3, fixed to a shaft 4, upon which latter shaft is secured the rotating clutch mechanism for the motor, so that the motor may be wound as the shaft 4 is rotated in one direction and when the shaft is released the motor will operate as the shaft moves in the opposite direction.

A scape-wheel 5 is fixed to the shaft a^2 for governing the speed of the motor. A crank-arm 6 is fixed to the winding-shaft 4, which is connected to one end of a pivoted starting-lever 7 by a link 8, the opposite end of the said starting-lever being provided with a finger-piece 9, the shank of which follows in a slot 10, cut in the face of the box. It will

thus be seen that as the starting-lever is depressed the motor will be wound and when let go the motor will operate to effect the rotation of the shaft a^2 , thereby rotating the contact-pen a .

A series of concaved signaling-surfaces b is adapted to be moved into the path of movement of the contact-pen, the said signaling-surfaces being herein shown as secured to a frame b' , which moves upon guide-bars b^2 , the upper side of the said frame being provided with a rack-bar b^3 , which is engaged by a pinion b^4 , secured to a shaft b^5 , to one end of which a pointer b^6 is secured and by which it is rotated. The shaft b^5 has on it at its opposite end a toothed wheel c , which is engaged by one end of a pivoted latch c' , the opposite end of said latch resting beneath the hooked end of the bent lever c^2 , pivoted at c^3 . The bent lever c^2 is moved by one or another stud c^4 , projecting from the face of the wheel 3 of the motor.

The bent lever c^2 and the means for moving it, together with the pivoted latch, forms a locking and releasing device substantially 75 such as shown in another application filed by me, Serial No. 238,459.

In operation, the pointer is moved over a dial marked upon the face-plate of the box to any desired signal and the starting-lever 80 operated, which effects the rotation of the contact-pen over that particular signaling-surface which is brought into the path of movement of the pen by the rotation of the pointer.

The box may be provided with a door of 85 any suitable construction, if desired.

A break-wheel w is mounted upon the shaft a^2 and a contact-pen w' is provided, the notched portion of the break-wheel being designed to transmit the box-number and occupying a position to change the condition of the circuit at the time the contact-pen a is moving over the long notched portion of the signaling-surface b , so that the box-number and signal will be transmitted one after the other.

I claim—

1. In a signal-box, a rotatable contact-pen, combined with a series of signaling-surfaces arranged on a frame or carrier which is movable in a direction parallel with the axis of 100

rotation of the contact-pen to present one or another signaling-surface to the contact-pen, a pointer connected to said frame or carrier for moving it, and a dial, substantially as described.

2. In a signal-box, a rotatable contact-pen, a series of movable signaling-surfaces, combined with a rack-bar, toothed wheel, and means for moving the toothed wheel, and a

locking and releasing device for the toothed wheel, substantially as described.

In testimony whereof I have signed my name to this specification in the presence of two subscribing witnesses.

JOHN. C. WILSON.
